RECHARGEABLE PORTABLE RADIO AND SEPARABLE CLOCK-CHARGER THEREFOR

Richard Culbertson, New Hartford, N.Y., assignor to
General Electric Company, a corporation of New
York

Filed Nov. 21, 1966, Ser. No. 4,751

Term of patent 7 years

(Cl. D56—4)

FIG.1

FIG.2

FIG.3

FIG.4

FIG.5

FIGURE 1 is a front, top and right side perspective view of a combined rechargeable portable radio and separable clock-charger therefor, showing my new design;

FIGURE 2 is a right side view;

FIGURE 3 is a front elevational view;

FIGURE 4 is a top view;

FIGURE 5 is an exploded front, top and right side perspective view similar to FIGURE 1 but showing the rechargeable portable radio removed from the clock-charger for separate operation thereof.

The legible matter in the drawings is shown in broken line form for illustrative purposes only.

I claim:

The ornamental design for a combined rechargeable portable radio and separable clock-charger therefor, as shown and described.
